Design
Chair of Molon's side of a Slave. Patented April 10, 1849.
No 218

Des. 218

Charles J. Woolson Cleveland Ohio
Letters Patent No 518 dated April 10th - 1853
The schedule referred to in these letters patent and making
part of the same.

To all whom it may concern: We claim that Charles
J. Woolson of Cleveland, Cuyahoga Co. Ohio have invented
a produced a new & useful design for the side of a cooking
stove; and I do hereby declare that the following is a full
and exact description, thereof, reference being had to the
accompanying drawings, in which the ornamental de-
sign thereon is clearly represented.

The shape & configuration of the plates are designated by
the general outline of the drawing. The outer edge of
the plate is surrounded by an ornamental border A.
The oven door is ornamented with scroll work and leafing
B. the part of said scroll work represented being sym-
metrical with the other part not shown. The fire door
has the figure of a Bird rising from a tree C. and in
each corner an ornamental spring D.

Having thus distinctly represented & described the nature
& arrangement of the respective ornaments and figures upon
the side plates of my cooking stove.

What I claim as new & desire to secure by letters patent
is the configuration & arrangement of said ornaments
as herein designated & represented.
